CARD-PUNCHING MACHINE.

1,061,883.

Specification of Letters Patent. Patented May 13, 1913.

Application filed December 4, 1911. Serial No. 863,871.

To all whom it may concern:

Be it known that we, STEPHEN B. TILY, JOHN G. REHFUSS, and MARTIN O. REHFUSS, citizens of the United States, residing in Philadelphia, Pennsylvania, have invented certain Improvements in Card-Punching Machines, of which the following is a specification.

One object of our invention is to provide a cash register of the type designed to punch holes in various positions in record cards to indicate the amount of a sale, the date, the cashier's designating number, the department, etc.; it being especially desired to provide a machine of the above noted character which shall be simple and substantial as to the number, arrangement and construction of its parts, and which shall not be likely to get out of order or to require but a minimum of attention and repairs.

We further desire to provide a punching cash register with novel means for supporting a card in position, prior to or while it is being punched, and which shall automatically operate to release the card to permit it to fall into a suitable container, after the punching operation has been completed.

It is further desired to provide a machine of the character described in which each of certain punches shall be directly carried upon an adjustable rack, which racks in turn shall, with their associated parts, be mounted on a punch head hinged to its supporting structure so as to be movable away from a die plate to permit of the inspection of the parts.

We further desire to provide mechanism which shall simultaneously release a cash drawer and operate punching mechanism, and in which the arrangement of parts shall be such that said drawer is locked as long as the punching mechanism is in its normal position.

We further desire to provide a machine of the above noted type with novel means for insuring the proper positioning of a card to be punched, and which shall have its parts so arranged that there shall be no possibility of a card dropping through the machine before the latter has been operated.

Another object of our invention is to so arrange the parts of a punching cash register that certain of the punches shall be conveniently removable and shall be nor-

mally held in place by a device, which in the absence of the punches, shall occupy such a position as to prevent operation of the machine.

These and other advantageous ends are secured as hereinafter set forth, reference being had to the accompanying drawings, in which—

Figure 1 is a perspective view of a cash register constructed according to our invention; Fig. 2 is a longitudinal vertical section of the machine shown in Fig. 1; Figs. 3 and 4 are respectively transverse vertical sections taken on the line a—a, Fig. 2, and looking in opposite directions; Figs. 5 and 6 are fragmentary horizontal sections illustrating the card positioning device in its normal and in its operative positions; Fig. 7 is a vertical section showing the card supporting device in its two extreme positions; Figs. 8, 9 and 10 are perspective views of the different forms of punch supporting structures used in our invention; Fig. 11 is a perspective view of one of the cards used in our machine; and Fig. 12 is a side elevation illustrating the detail construction of one of the parts of my invention.

In the above drawings 1 represents a box-like structure forming the base of our cash register and having slidable within it a drawer 2, which, as shown in Fig. 2 projects slightly more than half way through the base, and at all times tends to move outwardly under the action of a spring 3. In this instance the drawer has mounted within it a cash box 4, and is provided with a handle 5.

Rigidly fixed to the inner end of the drawer 2 preferably at one side, is a rearwardly extending bar 6, having a notch or recess in the end portion of its under edge for a purpose hereafter noted.

The rear part of the box-like base 1 is provided with a door 7, having a lock 7a and designed for the reception of the record cards after these have been punched by the machine.

Mounted on and rigidly fixed to the top of the box structure 1, is a metallic frame in the form of a hollow casting 8, provided with a pair of horizontal guides 9, in which is mounted a slide 10, carrying a die-plate 11 and provided on its under side with a rack 12. Meshing with this rack is a toothed

segment 13, fixed to a transversely extending shaft or spindle 14, within the casing 8, in which said spindle is rotatably mounted.

As shown in Fig. 1, the spindle 14 projects at one side on the casing 8, and has fixed on it an operating arm 15, normally held in an elevated position by a spring 16, coiled around the spindle 14, with one end fixed to the segment 13 and the other to the casing. This operating arm has mounted under it, adjacent the projecting end of the spindle 14, a plunger 17, guided by a bushing 18 set in the top of the box-like structure 1, into which the plunger extends; there being on the inner end of this plunger a lug provided by a projecting screw 19, so placed as to normally engage the recess in the edge of the bar 6, whenever the drawer to which this is attached is in its inner or closed position. Said plunger is at all times pressed toward this upper position by means of a spring 20, operative within the bushing 18, and is prevented from turning in said bushing by means of a pin 21, extending through a slot 22 in the plunger.

The slide 10 has formed on its inner end an upwardly projecting block or plate 23, on one face of which is fixed a pair of plates 11 and 24, spaced apart so as to provide a flat vertical cavity, for the reception of a card to be punched.

As shown in Fig. 4, a rectangular portion of one end of the plate 11 is provided with a number of vertically placed series of holes, each hole having a countersunk opening on the outer face of the plate, while the plate 24 similarly has an identically arranged plurality of series of punch holes, respectively in line with those of the plate 11, it being noted that the block 23 of the slide is recessed immediately adjacent to this second die plate, for the reception of the punchings passing through the same.

We preferably provide a small drawer or outwardly discharging chute under this recess 25, as indicated at 25^a, so that the punchings may be collected or permitted to automatically discharge themselves as may be advisable.

Pivotedly mounted on one end of the block 23 is a lever 26, held in place by a screw 27 and having its upper end made in the form of a turned-over finger 28, (Fig. 7,) so that it is capable of extending over the card-receiving cavity between the plates 11 and 24. The lower end of this lever is likewise bent over approximately at right angles to its length, as indicated at 29, and carries a transversely extending plate, 30, capable of being projected under the card receiving cavity between the plates 11 and 24, in order to temporarily support a record card therein. This part 29 of the lever with the plate 30, preferably lies in a cut-away portion of the top of the metal casing 8, which is trans-

versely slotted to permit of the passage of a card from the aforesaid cavity into the space 31 of the supporting box structure 1; there being provided an elongated flat tubular structure 32 within the casing 8 to insure the passage of a card through the same. If desired, some form of guiding abutment may be mounted adjacent the discharge end of this guide-way 32, as indicated at 33, whereby a card falling therefrom is given an inclination which results in its being deposited in a substantially horizontal position within the box 1.

It will be understood that the lever 26 is so formed and mounted that when in one of its extreme positions, its end 28 projects over the cavity 11^a between the plates 11 and 24, to such an extent as to prevent the introduction of a card thereto, although its end 29 is then in such a position as to freely permit the falling of a card out of the cavity. When the lever is in its other extreme position, the end 29 is projected directly under the cavity, 11^a and the end 28 then lies to one side of the plane of said cavity.

In order to best operate the lever when the slide which carries it is moved by the operating arm 15, we mount on one edge of the opening in the top of casing 8, under the plate 11, a pin 34, so that when the lever 26 is moved toward this edge, its plate 30 engages the pin and is held thereby a short distance away from the edge.

The punches are carried, as hereafter described, by a punch head 35, in the form of a structure of rectangular section extending upwardly on the top of the casing 8, and having a rearwardly projecting portion 36, hinged or pivoted to such casing by a hinged bolt 37. In order to hold the punch head in its normal operating position, we provide a locking bolt 38, slidably mounted in a suitable projection 39 on the top of the casing 8 and having a head 40, whereby it may be withdrawn from engagement with the punch head, against the action of a spring 41 which normally maintains it in such engagement.

As shown in Figs. 1 and 2, there are mounted within the vertically extending part 35 of the punch head a series of vertically movable racks 42, each carrying a single punch 43, which projects through a suitable slot in one face of the punch head, so as to be capable of entering any one of the punch holes belonging to a vertical series in the die-plates 11 and 24, when these latter are moved toward said punches. Each of the racks has operative on it a pawl 44, which engages its teeth under the action of a spring 45.

For moving the racks and with them the punches, we provide a spindle 46, mounted in suitable bearings on the punch head and carrying a number of toothed segments 47, 180

one for each of the racks 42, whose teeth engage the teeth of the respective racks. These segments, of which in the present instance there are four, have operating arms 48, 49, 50 and 51 and project through slots in a substantially semi-cylindrical casing 52 inclosing said segments 47 and their associated parts. Each of these slots has adjacent to its edge a line of figures, designed to indicate the position of the particular punch 43 attached to the arm 48, for example, which projects through said slot; the arrangement being such that if the arm 48 be moved to a point adjacent to the Fig. 4, for instance, the rack 42 with the punch 43 carried thereby is moved downwardly, so that said punch is brought into line with the fourth punch opening at the top of one of the vertical series of openings in the die plates 11 and 24. By this means it is possible to bring any one of the punches into line with any of the openings in its particular vertical series in the die-plates, as indicated by the figures on the casing 52 adjacent to the operating arms 48.

The punch head 35 is also provided with two vertical slots 53 and 54, through which projects a pair of handles 55 and 56, directly attached to two racks of the form indicated at 42^a in Fig. 10, each of which carries a punch 43. It is of course, obvious that these racks 42^a are toothed merely for the purpose of providing a ratchet to be engaged by one of the pawls 44, in order to retain it with its punch 43 in any given position. In order to operate these particular racks with their punches, it is merely necessary that their handles 55 or 56 be vertically moved in slots 53 or 54, as the case may be, into the desired position to bring the panels opposite any particular punch-hole of the corresponding vertical series in the die-plates 11 and 24.

The front face of the punch head, as shown in Fig. 3, has removably mounted in it a plate 60, formed with its ends inclined, carrying one or more punches, as shown in Fig. 8, and designed to fit into a cavity 50 whose upper end is under-cut, for the reception of the inclined end 60^a of said plate. Immediately under the bottom of this plate and pivoted to the punch head, is a spring actuated holding lever 61, so formed as to fit the inclined end of the plate 60 and at all times force it upwardly into its cavity. (See Fig. 12). It will of course, be understood that the punches on this plate are so arranged as to come opposite certain of the punch holes in die plates 11 and 24, it being our intention that each of the sales persons using the machine shall be provided with one of the removable plates 60, and that each of said plates shall have on it a different arrangement of permanently mounted

punches. It will further be noted that the lever 61 is so placed on its supporting structure that when the plate 60 has been removed, it is forced by its spring 62 into such a position that it is impossible to move the slide 10 with its die-plates sufficiently to permit of a card being punched. Thus, as shown in Fig. 12, the removal of the plate 60 permits this holding lever 61 to move upwardly far enough to interpose its end 70 63 in front of the die plate 11, thereby preventing this latter being moved sufficiently far to allow the punches entering the holes.

For the purpose of insuring that the cards introduced into the cavity 11^a shall always have their parts to be punched in the proper position relatively to the various series of punches, we provide means whereby said cards are moved toward one end of this cavity before being engaged by the punches. For this purpose, we mount on the casing 8, a wedge-shaped bar 65, suitably fastened by screws 66 to the top surface of the casing and having a portion projecting into that end of the cavity 11^a which is most distant from the punches; it being noted that as the slide with its die-plates is moved toward the punch head, this wedge shaped bar enters the end of the cavity sufficiently far to cause its inclined surface to act on the end of the card therein.

Under conditions of use, it will be understood that the drawer 2 is normally locked shut by the hook bar 6, and that the slide cannot be moved toward the punch head 100 until one of the plates 60 has been introduced into its cavity and so engaged by the lever 61, that the latter is moved down out of the path of movement of the die-plate 11.

The cards which it is intended to use with this machine, while being made in many different forms, may be made up as shown in Fig. 11, with four columns of figures running from zero to nine, and a definite space for the punches indicating the cashier, as well as other spaces for the punches indicating the day and month.

If now it be desired to record a sale on a card of the form shown in Fig. 11, the lever 26 would be so moved as to permit of said card being dropped into the cavity 11^a, wherein it would rest upon the lower arm 29 of said lever. The cashier having inserted her designating plate 60 in the punch head and moved the racks 42^a by means of their handles 55 and 56 to designate the proper date of the month, would thereafter move one or more of the operating arms 49, 50, or 51, so that these would be opposite such numerals on the casing 52 as would correspond with the amount of the sale which it is desired to record. This movement of the operating arms, as well as of the handles 55 and 56, brings the corresponding punches 43 into line with corre- 130

4

sponding holes in the die-plates 11 and 24. When the operating arm 56 is pushed downwardly, the card is first moved longitudinally in the slot 11^a, by reason of the engagement of one of its ends with the inclined surface of the bar 65, and its opposite end is certainly pressed tightly against the corresponding end of the cavity, thus insuring that the vertical series of numerals on the card X is in line with the corresponding vertical series of punch holes in the die-plates. The continued downward movement of the operating arm 15 then forces the punches through the die-plate 11, through the card and into the die-plate 24, thus punching out one numeral in each of the four vertical columns on the card, besides making certain holes in predetermined positions to designate the cashier operating the machine, and also making other holes to designate the day and month. This moving forward of the slide 10 with its die-plates, brings the pins 34 into engagement with the plate 30 of the lever 26, moving the upper end of said lever over the cavity 11^a, so that when the operating arm 15 is released and the slide with its attached part is moved back to the normal position shown in Fig. 2 under the action of the springs 20 and 16, the card, which had been supported first on the lower end 29 of the lever and afterward on the top surface of the casing and by the punches, is left without support, owing to the withdrawal of the punches and the movement of the die-plates over the opening to the guideway 32. The card then falls through the said guideway into the interior of the space 31 of the box structure 1, engaging the abutment 33 as it falls, so that it is deposited in a substantially horizontal position. At the same time that the operating handle is pushed down to move the slide and the die-plates toward the punches, the plunger 17 is also depressed by said handle, thus moving the hook lug or screw 19 out of engagement with the recess of the hook bar 6, and permitting the spring 3 to push the drawer outwardly. It is of course obvious that this spring may be omitted, so that it is necessary to open the drawer by hand, though in any case it is to be noted that said drawer is unlocked by a movement of the operating arm which causes the punches to act, to cause the punching operation to take place simultaneously with the unlocking of the drawer. The bar 6 is so formed at its end that if the operating arm 15 should be allowed to return to its upper position before the drawer 60 was shut, it could still be returned to its closed position, since the inclined end, by engaging the projection formed by the screw 19, could be made to draw the abutment 17 downwardly until said projection 65 entered the recess in said bar.

As will be understood by those skilled in the art, the cards punched by our machine are delivered in large numbers to automatic sorting and recording machines of a well-known form, whereby all those cards 70 punched to indicate the sales of a particular salesperson are collected by themselves and if desired, separately totaled.

We claim:

1. The combination in a card punching 75 machine, of a punch head; a series of longitudinally movable members mounted on said head; a punch carried on each member; a structure having a die plate and formed to support a card; and means for moving said structure and said punch relatively to each other to punch a card.
2. The combination in a card punching machine, of a receptacle; card punching mechanism; and a lever actuated by said mechanism and mounted to automatically discharge cards into said receptacle after they have been punched. 85
3. The combination of a receptacle; card punching mechanism mounted over the same; a lever for supporting a card while it is being punched; and means for moving said lever to permit the card to pass into the receptacle after said card has been punched. 90
4. The combination in a card punching 95 machine, of a receptacle; card punching mechanism mounted to discharge cards to the receptacle; said mechanism including a structure for holding the card while it is being punched; a member mounted to support a card in said structure; and means for withdrawing said member to permit the card to drop into the receptacle when the machine is operated. 100
5. The combination in a card punching 105 machine, of a receptacle, card punching mechanism mounted to discharge cards into said receptacle and including a card holder; a movable member having a portion capable of extending under the holder to support a card therein and movable to release a card; said member also having a portion extended to prevent the introduction of the card to the holder until the said first portion is moved to its card supporting position; and means for actuating the member to release the card when the machine is operated. 110
6. The combination in a card punching 120 machine, of a supporting structure; a series of toothed bars adjustably mounted in said structure; a punch carried by each bar; pawls respectively operative on the bars for retaining the punches thereof in any of a number of adjusted positions; a structure for supporting a card; and means for moving the card supporting structure relatively to the punch supporting structure to cause a card carried by the former to be punched. 125
7. The combination in a card punching 130 machine, of a supporting structure; a punch

- head mounted thereon and connected thereto by a pivot; a series of punch carrying members adjustably mounted in said head; means for detachably locking the head in an operative position; a card holder on the supporting structure; and means for causing said holder to bodily move relatively to the head to cause the card carried thereby to be punched.
- 10 8. The combination in a card punching machine, of a supporting structure; a punch head mounted thereon; a series of punches adjustably mounted on the head; a card holder also mounted on said structure; and means for bodily moving one of the two parts comprised by a punch head and the card holder toward and from each other; the other of said parts being pivotally mounted on the supporting structure to permit of its being swung away from the second part.
- 15 9. The combination of a supporting structure; a punch head pivotally connected thereto; means for locking said head in a predetermined position; a series of bodily movable punches adjustably carried by said punch head; a card holder slidably mounted on the supporting structure; and means for bodily moving said card holder toward and from the punch head.
- 20 10. The combination in a card punching machine, of a supporting structure; a punch head mounted thereon; a series of punches adjustably carried on said head; a card holder mounted on the supporting structure and free to move toward and from the punch head; a lever pivoted to said holder and having two arms of which one is capable of extending under the holder to support a card, and the other is capable of extending over the holder to prevent placing a card therein until said lever is moved into a position to bring the other arm under the holder; a structure mounted to move the lever to cause the card supporting arm to release a card when the holder is moved relatively to the punch head and means for moving the card holder and the punch head relatively to each other.
- 25 11. The combination in a card punching machine, of a supporting structure; a series of independently adjustable punches carried thereby; a card holder; means for moving the card holder relatively to the punches to cause the latter to operate on a card; with means actuated from said holder - moving means for placing the card in a predetermined position in the holder after its insertion and before the punches act thereon.
- 30 12. The combination in a card punching machine, of a supporting structure; a series of independently adjustable punches mounted on said structure; a card holder; means for moving the punches and the card holder relatively to each other to cause said punches to act on a card in the holder; and a wedge shaped member mounted to be brought into engagement with a card in the holder prior to its engagement by the punches to move said card to a predetermined position in the holder.
- 35 13. The combination in a card punching machine, of a supporting structure; a punch head mounted thereon; a series of independently adjustable punches mounted in said head; a card holder slidably mounted on the supporting structure and having a die plate; a cam mounted on the structure in position to project into the card holder when the latter is moved; and means for moving the holder toward the punches to cause the latter to act on a card therein; said cam being placed to force a card in the holder to a predetermined position when the machine is operated.
- 40 14. The combination in a card punching machine, of a supporting structure; a punch head mounted thereon; a series of punches adjustably mounted on the head; a piece carried by the head and provided with a fixed punch; a member engaging said piece to hold it removably to the head; a card holder mounted on the supporting structure; means for moving the card holder and the punch head relatively to each other to cause the punches to act on a card carried by the holder; the member for holding the said punch carrying piece being mounted to move into position to prevent operation of the machine in the absence of said piece.
- 45 15. The combination in a card punching machine, of a punch head having a removable piece; fixed punches on said piece; means for operating the machine to punch a card; and a movable element capable of projecting into a position to prevent operation of the machine but normally held out of such position by said removable piece.
- 50 16. The combination in a card punching machine, of a supporting structure; a punch head carried thereby; a series of punches adjustably carried by the head; a piece carried by the head and provided with a plurality of punches; a spring actuated member normally holding said piece in place; a card holder; and means for moving the punch head and the card holder relatively to each other to cause the punches to operate on a card; said spring pressed member being free to move into a position between the punch head and the card holder when the punch carrying piece is removed, to prevent the punches operating on a card.
- 55 17. The combination in a card punching machine, of a supporting structure; a punch head hinged thereto and having a recess; a piece fitting said recess and having card punching means; a series of punches adjustably carried by the punch head; a card holder slidably carried by the structure;

means for moving said card holder toward and from the structure; and a member carried by the punch head to normally hold the movable piece in its recess; said member being normally held by said piece out of the path of the card holder but being movable into said path to prevent operation of the machine in the absence of said piece from the punch head.

10 18. The combination in a card punching machine, of a hollow supporting structure; a punch head hinged thereto; a bolt for locking said punch head in an operative position; guides on the supporting structure; a slide operative in said guides and provided with a rack; a card holder carried by the slide and including a die plate; a series of punches adjustably carried by the punch head in position to coöperate with the die plate; a shaft mounted in the supporting structure; a toothed segment fixed to said shaft and meshing with the rack on the slide; and an operating arm also fixed to the shaft for operating the same.

25 19. The combination in a card punching machine, of a punch head; a card holder; means for moving the said card holder relatively to the head; punches carried by the head for operating on a card in the holder; 30 a card receptacle placed to receive cards from the holder after they have been punched; and card-guiding means for causing the cards to be deposited in planes substantially at right angles to that in which

they are supported in the holder and one 35 over the other in the receptacle after they pass from the holder.

20. The combination in a card punching machine, of a supporting structure; a punch head mounted thereon; a series of punches 40 adjustably mounted on the head; a piece removably carried by the head and provided with a fixed punch; a card holder on the supporting structure; and means for moving the card holder and the punch head relatively to each other to cause the punches to act on a card carried by the holder.

21. The combination in a card punching machine, of a supporting structure; a punch head mounted thereon; a series of punches 45 adjustably mounted on the head; a plate having punches and fitting an undercut recess in the head; means for removably holding said plate in such recess; a card holder on the supporting structure; and means for moving the card holder and the punch head relatively to each other to cause the punches to act on a card carried by the holder.

In testimony whereof, we have signed our names to this specification, in the presence 50 of two subscribing witnesses.
